Patented May 8, 1962

192,729

AUTOMOBILE TOP

Daniel Marvosh, 3162 N. Rosemead Blvd.,
Rosemead, Calif.

Filed July 25, 1960, Ser. No. 61,496

Term of patent 14 years

(Cl. D14—27)

FIG. 1 is a perspective view of an automobile top showing my new design;

FIG. 2 is a side elevational view thereof;

FIG. 3 is a front elevational view thereof;

FIG. 4 is a rear elevational view thereof;

FIG. 5 is a top plan view thereof;

FIG. 6 is a bottom plan view; and

FIG. 7 is a fragmentary sectional view thereof taken on line 7—7 of FIG. 4.

I claim:

The ornamental design for an automobile top, substantially as shown.
